Atty.

UNITED STATES PATENT OFFICE.

ALICE NE COLA LUDWIG, OF MARKVILLE, MINNESOTA.

DESIGN FOR A DOLL.

58,787.

Specification for Design.

Patented Aug. 30, 1921.

Application filed May 4, 1921. Serial No. 466,706. Term of patent 7 years.

To all whom it may concern:

Be it known that I, ALICE NE COLA LUDWIG, a citizen of the United States, residing at Markville, in the county of Pine and State of Minnesota, have invented a new, original, and ornamental Design for Dolls, of which the following is a specification, reference being had to the accompanying drawing, forming part thereof.

In the drawings—

Fig. 2 a side elevation showing the new design for a doll.

I claim:—

The ornamental design for a doll, as shown.

ALICE NE COLA LUDWIG.
